UNITED STATES PATENT OFFICE

ROSA BURNS, OF DALLAS, TEXAS

SEPARABLE BUCKLE

Application filed April 25, 1930. Serial No. 447,249.

This invention relates to new and useful improvements in separable buckles and more particularly to devices of this character which are for use on strips of elastic material to be inserted through hems or loops provided in the waist band and the legs of undergarments such as bloomers.

The primary object of the invention is to provide, in a manner as hereinafter set forth, 10 a separable buckle of the aforementioned character which is connected to the free ends of a flexible strip for detachably connecting said ends together, one of the buckle elements being formed to constitute a bodkin to facilitate the insertion of the band through the 15 hem or loop of a garment.

Other objects of the invention are to provide a separable buckle of the character described which will be simple in construction, 20 strong, durable, efficient in its use and which may be manufactured at low cost.

All of the foregoing and still further objects and advantages of the invention may become apparent from a study of the following specification, taken in connection with the accompanying drawing wherein like characters of reference designate corresponding parts throughout the several views, and wherein:—

30 Figure 1 is a view in top plan showing the opposite end portions of a garment band or strip with the separable buckle mounted thereon and connected together.

Figure 2 is a view in front elevation there- 35 of.

Figure 3 is a detail view in perspective of one of the buckle elements detached from the band.

40 Figure 4 is a detail view in perspective of the other of the buckle elements detached from the band.

Referring to the drawing in detail, it will be seen that the reference numerals 1 and 2 45 designate the opposite end portions of an elastic band or strip which are detachably connected together through the medium of a buckle which is designated generally by the reference numeral 3.

The buckle 3 comprises an elongated, flat 50 plate 4 having a transverse slot 5 in one end

portion thereof through which the end portion 1 of the band is passed, said end portion being folded back and stitched upon itself, as at 6. In spaced relation to the slot 5, the plate 4 is further provided with a comparatively large opening 6' and said plate terminates in a pointed free end portion 7. The configuration of the plate 4 adapts the same to function as a bodkin when inserting the band in the garment. 55

The buckle 3 further includes an elongated, flat plate 8 having a transverse slot 9 adjacent one end through which is passed the end portion 2 of the band, said end portion being folded upon itself and stitched, as at 60. 10. The plate 8 also terminates in a substantially pointed free end portion 11. A resilient connecting tongue 12 is struck out from the plate 11 and is directed rearwardly in spaced, substantially parallel relation to 65 said plate. The tongue 12 constitutes a hook adapted for insertion through the opening 6' of the plate 4 for connecting said plate together in the manner clearly illustrated in Figures 1 and 2 of the drawings. When 70 inserted through the opening 6' the tongue 12 is disposed closely adjacent the opposed face of the plate 4 and in parallelism therewith to prevent the same from catching on objects which may come in contact with the 75 buckle. While the element of the buckle 12 may be formed of any desired material, the same are preferably constructed of suitable spring metal.

It will thus be seen that I have provided a garment band having fastening means connected thereto of a construction and arrangement whereby the band may be expeditiously inserted in a garment and the ends thereof connected together. As before stated, the plate 4 is utilized as a bodkin when inserting the band in the garment. 85

It is believed that the many advantages of a garment band constructed in accordance 90 with this invention will be readily understood, and although the preferred embodiment of the invention is as illustrated and described, it is to be understood that changes 95 in the details of construction may be had 196

which will fall within the scope of the invention as claimed.

What is claimed is:—

As a new article of manufacture, a separable buckle comprising co-acting, flat metallic plates each having an opening in one end portion for connection with the ends of a flexible strip, said plates being adapted for disposition in opposed relation to each other and having pointed free ends, an integral, laterally and rearwardly directed resilient retaining tongue struck out from an intermediate portion of one of the plates, the rearwardly directed portion of the tongue being disposed in spaced, opposed substantially parallelism with said one plate, the other of the plates being provided with an opening in its intermediate portion for the reception of the tongue in a manner to readily secure the plates together in opposed relation, said other plate constituting a bodkin adapted to facilitate the insertion of the flexible strip in a garment.

In testimony whereof I affix my signature.
